UNITED STATES PATENT OFFICE.

FREDERICK H. MEIER, OF WEBSTER CITY, IOWA.

SECTIONAL CLAY BLOCK STRUCTURE FOR SEWERS AND DRAINAGE.

Application filed May 29, 1919. Serial No. 300,604.

To all whom it may concern:

Be it known that I, FREDERICK H. MEIER, a citizen of the United States, and a resident of Webster City, in the county of Hamilton and State of Iowa, have invented a certain new and useful Sectional Clay Block Structure for Sewers and Drainage, of which the following is a specification.

The object of my invention is to provide a clay tile or culvert or other circular structure made of a plurality of sections adapted to be manufactured in the factory and assembled into a completed structure on the job.

More particularly it is my object to provide such a structure in which the sections are preferably formed with an outer and inner wall with air spaces between them, and with suitable transverse connecting members, the sections being provided at their adjacent ends with coacting extensions and openings, whereby the sections may be mortared together and interlocked, the parts being so arranged that at each joint there may be made a post of concrete or the like arranged longitudinally of the completed structure, for locking the sections together.

Another object is to provide such a structure in the form of a tile or the like, in which the joints are exceedingly strong and well-connected.

With these and other objects in view my invention consists in the construction, arrangement and combination of the various parts of the device, whereby the objects contemplated are attained, as hereinafter more fully set forth, pointed out in my claims and illustrated in the accompanying drawings, in which:

Figure 1 shows an end elevation of a culvert or tile embodying my invention.

Figure 2 shows a front elevation of one of the sections set up on end viewed from the outside.

Figure 3 shows a perspective view of one of the sections; and

Figure 4 shows a detail, sectional view taken on the line 4—4 of Figure 1.

It will be understood that my sectional structure may be made in larger or smaller sizes, so that it may be used for drain tile, culverts, and sewer pipe for sanitary and storm sewers.

The structure which embodies my inven-

tion is made up of sections, one of which is shown as viewed from the inside in perspective in Figure 3. Each section preferably has an inner wall 10, and an outer wall 11, said walls being curved on the arcs of circles having their centers at the center of the completed structure. The walls 10 and 11 are connected by cross walls such as are illustrated at 12, 13 and 14.

In the original construction of each section as it comes from the die in the clay works, there is connected with each wall 10 and 11 and inset therefrom a wall 15 and a wall 16, which are connected at their outer ends by a cross wall 17.

The portions which connect the walls 16 with the walls 11, and the walls 15 with the walls 10, are indicated in Figure 3 by the reference characters 18 and 19. It will thus be noticed that in the completed structure, there is provided at each side edge of each section a longitudinal extension, which is not so thick as the main body of the section.

In completing each section portions of each extension are cut away by using wires or the like mounted on a suitable frame. One cut is made through the portions 18, and one through the portion 19 for separating the walls 16 and 15 from the walls 11 and 10.

Transverse cuts are made for getting out portions of the extensions hereinbefore described.

When the section is completed it will be noticed that at one edge it has a series of extensions A spaced from each other longitudinally of the section, and at the other edge a series of similarly spaced extensions B. The extensions B, however, are staggered with relation to the extensions A.

In assembling the tile or the like on the work the sections are set up on end and placed together, as illustrated in Figure 1, with the extensions B fitting into the spaces between the extensions A of an adjacent section, and with the walls 10 of adjacent sections fitting snugly together and with the walls 11 of adjacent sections fitting snugly together.

It will be noted that when the parts are thus assembled, there will be found extending down through the overlapping extensions A and B a continuous opening 20, extending longitudinally through the completed tile or the like. This opening in the

completed structure is preferably filled with slush cement 21 or the like, but any suitable material for the purpose may be employed.

5 It will be noted that in each member A and B, the opening 20 extends circumferentially in the tile across the joints between the adjacent tile sections.

It will also be noted that the partitions 10 12 and 14 extend longitudinally of the sections from end to end thereof. It thus follows that the locking post made by pouring slush concrete or the like into the opening 20 will have portions which project circumferentially of the completed structure in both directions from the lines of the joint between adjacent sections.

Special attention is called to this structure in connection with the staggering of the 20 members 17 of the adjacent sections and the reducing of the thickness of the members 17 from the inside to the outside of the tile. This combination finishes a tile with an internal and interlocking joint, which on the 25 outside and inside appears to be simply on a continuous longitudinal line, but which is, in fact, extremely strong, because of the support, the member 17 gives to the outer and inner shells of the members.

30 After the joint has been finished by pouring the slush concrete, it will be seen that it would be very difficult to break the tile or the like at the joint.

It is obvious that a wooden strip might 35 be used if desired.

By means of the concrete or the like 21 the sections are locked together and the completed tile is made.

It will be noted that while the extensions 40 A and B overlap each other, they cannot be seen except at the ends of the tile or when the tile is completed.

On the inside and outside of the tile there 45 can be seen only the longitudinal joints between the sections.

It will be noted that the joints between the different sections are very strong, and that strong shoulders are provided which will not easily tear off, and that the concrete or the like 21 forms a reinforcing post 50 for strengthening the sections at the joints as well as for holding them together.

It will be noted that one important feature of my invention arises from the fact 55 that the thickness of the extensions A and B from inside to outside is such that a cut may be made through the portions 18 and 19 in the plane of the outer surfaces of the wall members 16 and 15, and this cut will sever 60 the walls 16 and 15 from the walls 11 and 10.

Some changes may be made in the construction and arrangement of the parts of my improved sectional tile without departing 65 from the essential features and purposes of my invention, and it is my inten-

tion to cover by my claims any modified forms of structure or use of mechanical equivalents which may be reasonably included within their scope.

I claim as my invention:

1. In a device of the class described, a plurality of sections of plastic material, each comprising an inner and outer wall and transverse connecting walls, each section having at each side a plurality of projecting hollow tongues spaced from each other longitudinally of the section and thinner than the body of the section, each tongue being spaced from the adjacent transverse wall, so as to leave a hollow space in the tongue and in the adjacent body portion of the section extending from the interior of the tongue beyond said tongue and into the interior of the body of the section, the tongues on one side of each section being staggered with relation to the tongues on the other side thereof, said sections being arranged in a tile or the like, comprising a plurality of sections arranged in a circle with the tongues of the side edges of each section projected between and beyond the tongues of the side edges of the adjacent section and into the bodies of the adjacent sections.

2. In a device of the class described, a plurality of sections of plastic material, each comprising an inner and outer wall and transverse connecting walls, each section having at each side a plurality of projecting hollow tongues spaced from each other longitudinally of the section and thinner than the body of the section, each tongue being spaced from the adjacent transverse wall, so as to leave a hollow space in the tongue and in the adjacent body portion of the section extending from the interior of the tongue beyond said tongue and into the interior of the body of the section, the tongues on one side of each section being staggered with relation to the tongues on the other side thereof, said sections being arranged in a tile or the like, comprising a plurality of sections arranged in a circle with the tongues of the side edges of each section projected between the tongues of the side edges of the adjacent section and into the bodies of the adjacent sections, and plastic material received in said openings.

3. In a device of the class described, a tile comprising a plurality of sections of plastic material, each section having an inner and outer wall, and transverse connecting walls near its sides and having at each side a plurality of projecting hollow tongues, spaced from each other longitudinally of the section and thinner than the body of the section, the opening in each tongue being in communication with the opening between the inner and outer walls of its section, and being narrower than the opening between the walls of the section substantially as shown

for leaving a hollow space in the tongue and in the adjacent section, the tongues on one side of each section being staggered with relation to the tongues on the other side there-
5 of, the sections being arranged in a tile with the tongues of each section projecting be-
tween the tongues of the adjacent section into

the bodies of the adjacent section, and plas-
tic material received in said openings, for
forming posts in the tongues, and project- 10
ing into the bodies of the adjacent sections.

Des Moines, Iowa, April 28, 1919.

FREDERICK H. MEIER.
